John D. Sprague.

UNITED STATES PATENT OFFICE.

GEORGE R. URIDGE, OF DETROIT, MICHIGAN.

SMOKE-CONSUMING FURNACE FOR STEAM-GENERATORS.

SPECIFICATION forming part of Letters Patent No. 373,502, dated November 22, 1887.

Application filed May 12, 1887. Serial No. 237,953. (No model.)

To all whom it may concern:

Be it known that I, GEORGE R. URIDGE, of Detroit, in the county of Wayne and State of Michigan, have invented new and useful Improvements in Boiler-Furnaces; and I do hereby declare that the following is a full, clear, and exact description thereof, reference being had to the accompanying drawings, which form a part of this specification.

10 This invention relates to certain new and useful improvements in boiler-furnaces.

As furnaces for steam-generators are ordinarily constructed for burning coal, a large proportion of the products of combustion pass 15 to the exit-flue or smoke-stack unconsumed, and are therefore a dead loss. This more especially appertains to the use of soft or bituminous classes of coal, which in the progress of combustion throw off extraordinarily 20 large quantities of gases, which might be utilized to the great saving of fuel provided the proper kind of furnaces and appliances therefor are provided.

The invention consists in the peculiar construction, arrangement, and combination of 25 the various parts, as more fully hereinafter described, shown, and claimed.

Figure 1 is a longitudinal central sectional view of my improved furnace. Fig. 2 is a 30 cross-section on the line $\alpha\alpha$ in Fig. 1.

In the drawings which accompany and form a part of this specification, A represents the brick walls of a boiler-furnace, adapted to sustain the boiler B in position. This furnace is 35 provided with an ash-pit, C, grate-bars D, combustion-chamber E, feed-door F, and draft-door G, all of the usual construction, the rear end of such grate-bars resting upon the bridge-wall H. Extending laterally across the furnace from side to side and above the bridge-wall are two air-chambers, I and I', opening 40 through the side walls of the furnace, such openings being provided with doors J. The former of these air-chambers has perforations 45 in the top to discharge air when the opening leading into such chamber is disclosed into the products of combustion as they pass from the combustion-chamber E over the top of the bridge-wall, and the chamber I' has a similar 50 discharge in its rear wall for a similar purpose, except that the discharge of air through such rear wall is into another combustion-chamber,

K, which is provided with grate-bars L, one end of which rests upon the bridge-wall and the other upon the fire-brick wall M, supported by an arch, N, leading into a smoke-chamber, which communicates with the smoke-stack directly or through the flues of a boiler when a boiler of such construction is used. Above the wall M, which may be termed a 55 "subsidiary" bridge-wall under certain circumstances, is a direct-draft opening, P, having a damper, R, secured to a suitably journaled rock-shaft, S, one end of which projects through the side wall of the furnace and has a 60 handle or hand-wheel, T, attached thereto for the purpose of operating the damper R.

In the side wall of the auxiliary furnace, composed of the combustion-chamber K, grate-bars L, and ash-pit U, there is arranged a feed-door, V, through which coal may be fed onto the grate-bars, and a draft and ash-pit door, W.

Fire is made upon the grate-bars D with the direct draft P open, and the combustion-chamber E is designed to be somewhat longer 75 than the combustion-chamber K. A smaller fire is made upon the grate-bars L, and as soon as the fire in the latter becomes incandescent the direct-draft damper R should be closed, when the products of combustion from 80 the chamber E will pass over the top of the bridge-wall H, surmounted by the air-chambers, and the openings into such air-chambers being disclosed sufficient air will be mingled with such products of combustion to render 85 their ignition and perfect combustion practicable as they pass down through the fire upon the grate-bars L and through the arch N into the smoke-chamber O.

By this construction and operation nearly 90 or quite all the gases thrown off from the coal in the chamber E will be consumed and utilized under the boiler, thereby effecting great economy in fuel.

What I claim as my invention is— 95

1. In a boiler-furnace, and in combination therewith, an auxiliary combustion-chamber having a grate-bar and an ash-pit with suitable openings or doors leading thereto, and a double air-chamber upon the dividing bridge-wall and perforated, as shown, substantially 100 as and for the purposes described.

2. In a boiler-furnace, and in combination, a furnace under the front end of the boiler, a

subsidiary furnace in the rear of the furnace proper and divided therefrom by a bridge-wall and a lateral perforated air-chamber on the top thereof, a direct-draft opening controlled by a damper operating from outside the furnace-wall, and a communication between the ash-pit of the subsidiary furnace and the smoke-chamber, the parts being arranged and operating substantially as and for the purposes specified.

3. A boiler-furnace consisting of the ordinary combustion-chamber E, grate-bars D, and ash-pit C, having fuel-feed door and draft-door, and bridge-wall extending laterally across said furnace from side wall to side wall, surmounted by two air-chambers, perforated

as shown, communicating with the atmosphere through the side walls, a subsidiary combustion-chamber having grate-bars and ash-pit with doors leading thereto, a fire-brick wall in rear of the auxiliary chamber supported upon an arch, and having in its upper end a direct-draft opening controlled by a damper or valve operated from outside the furnace-walls, the parts being constructed, arranged, and combined substantially as and for the purposes set forth.

GEORGE R. URIDGE.
